UNITED STATES PATENT OFFICE.

RICHARD STINSON, OF ATHOL, MASSACHUSETTS, ASSIGNOR TO HEYWOOD-WAKEFIELD COMPANY, OF BOSTON, MASSACHUSETTS, A CORPORATION OF MASSACHUSETTS.

DESIGN FOR A BABY-CARRIAGE BODY.

Application filed October 20, 1927. Serial No. 23,824. Term of patent 3½ years.

To all whom it may concern:

Be it known that I, RICHARD STINSON, a citizen of the United States, residing at Athol, in the county of Worcester and Commonwealth of Massachusetts, have invented a new, original, and ornamental Design for a Baby-Carriage Body, of which the following is a specification, reference being had to the accompanying drawing, forming part

thereof, in which the single figure is a perspective view of a baby-carriage body, showing my new design.

I claim:

The ornamental design for a baby carriage body, as shown.

Dated this 14th day of October, 1927.

RICHARD STINSON.
